PRINTING PRESS

Henry A. Wise Wood, deceased, late of New York, N. Y., by Elizabeth Ogden Wood, executrix, New York, N. Y., and Charles L. Ricards, South Plainfield, N. J., assignors to Wood Newspaper Machinery Corporation, Plainfield, N. J., a corporation of Virginia

Application May 31, 1939, Serial No. 276,702

4 Claims. (Cl. 101—176)

This invention relates to improvements in a printing press and is particularly applicable when employed in connection with a high speed press such as used by most metropolitan newspapers.

The principal objects of the invention are to provide a press which operates at high speed with means contained within itself for preventing the fine mist of ink which, by the action of centrifugal force, is apt to be distributed by such a press, from being thrown outside the press where it can do any damage; to make the inking mechanism and printing couple readily accessible to facilitate adjustment, moving of rollers or cleaning; to construct a press of this type in which the arch is formed as usual and the inking system constitutes the sides of the arch; to locate the ink reservoirs or fountains in the lower end of this arch at the sides approximately at floor level; to guide the web through the press in such a manner that it will not be affected by the ink fog; to make the press easily accessible for reaching the web and allow the pressman to reach various parts of the press readily; to arrange the fountain regulating keys at a sufficient height to permit adjustment without the necessity of reaching down to the press floor or reaching down unduly; to provide access to the main fountain keys so that sections of them can be removed; to permit application of a special color fountain, and to provide the press with a cover employing a part of the press frame to cooperate therewith which will effectively enclose, not only the press, but particularly the inking mechanism and yet provide such cover with doors to make the parts accessible for adjustments and the like.

Other objects and advantages of the invention will appear hereinafter.

Reference is to be had to the accompanying drawings, in which

Fig. 1 is an end view of an arch type high speed press embodying the principles of this invention;

Fig. 2 is a side view of the same;

Fig. 3 is an enlarged end view showing one side;

Fig. 4 is a side view of larger scale than shown in Fig. 2;

Fig. 5 is a sectional view on the line 5—5 of Fig. 7;

Fig. 6 is a sectional view on the line 6—6 of Fig. 1;

Fig. 7 is a sectional view on the line 7—7 of Fig. 2;

Fig. 8 is a transverse sectional view of the ink fountain showing the inking system in diagram;

Fig. 9 is a similar cross section of the ink fountain employing an additional fountain for color;

Fig. 10 is a partial sectional view on the line 5 10—10 of Fig. 11, showing the fountain roll drive;

Fig. 11 is a plan of the same, and

Fig. 12 is an elevation of the construction shown in Fig. 9 in which the auxiliary fountain is assembled with the regular fountain.

10 The invention is shown as applied to a high speed newspaper printing press of the type in which the press is arch-like in end elevation and that is the type of press to which this invention is particularly, but not exclusively, adapted. At 15 the speed developed by such a press centrifugal force overcomes the surface tension of the ink to a certain degree and a mist or fog is produced, especially in the lower section of the inking mechanism. It is partly to avoid injury to the web 20 by this fog and the spreading of the fog outside the press that several of the features of the invention are employed. The type of press shown receives the web W from below and it is threaded between the two inking mechanisms and through 25 the rolls of the printing mechanism, in the manner shown, being discharged near the top.

In Figs. 1 and 2, a thin metal guard or cover 1 is made to coincide with the outline of a press side frame 2 to effectively conceal the ends of the 30 plate, impression cylinders, and the ink drums, or anything attached to said parts. Referring particularly to Fig. 5 for a clearer diagram of this arrangement it will be noted that the press side frame is carved or hollowed out to accommodate various parts within the depressions.

A plate cylinder 3, which is rotatably mounted in the side frame 2 by bearings 4, is driven by a gear 5 which is attached to the end of the cylinder 3 and is within the hollow of the frame 2.

40 Ink drums 6, 7 and 8 are carried within the frame 2 by bearings 9, 10 and 11 in such manner that they can be moved longitudinally as well as rotated. Fig. 5 shows that the mechanism which causes the ink drums to be moved longitudinally is carried inside of a hollow of the frame 2.

The cover 1 seals the above mentioned parts within the frame 2, making an oil tight arrangement. Said cover is made in sections for easier assembly. Joints are made with double seats 12 50 and 13 which form a chamber in which oil that may pass through the joint 13 can collect and then drain off through an opening 14.

It will be understood that the frame construction is similar for both ink motions, and that the 55 frame arrangement at the opposite end of the

cylinder and ink drums is constructed in like manner to accommodate any parts attached to said cylinders or drums.

A cover of this design has an arched opening beneath the press. To enclose this portion of the machine, hinged doors 15 on the press drive side, and hinged doors 17 on the end of the press opposite to the drive, are used. Said doors are hinged by hinges 16 to the cover 1 and suitably shut off this space on both ends of the press unit, but at the same time make it possible to reach parts inside of the unit. Figs. 1, 6 and 7 illustrate the construction of these doors and end cover.

The doors and end cover are shown in Fig. 6 as curved to pass around drive shaft tube 28. Locking handles 21 and 22, Fig. 1, will fasten the doors securely when closed.

In Fig. 7 the doors are shown flat to coincide with the cover on that end of the press. Handles 23 secure the doors 17 in place.

The right and left hand sides of the press, as shown in Fig. 1, are constructed in a similar manner so that the description of one side will serve for both. Fig. 1 shows that the guards extending from the floor to a point over the plate cylinder 3 are made in a number of sections.

A stationary cover section 19 supports a plurality of fountain blade adjusting screws 28 and keys 25 and covers the lower outside part of the ink motion. These screws adjust fountain blades 24. Said section is held in position by a channel 26 secured to the side frame 2 by a bracket 27. Said channel protects the keys 25 of the adjusting screws 28 which are placed in a reasonably high position, thereby eliminating the necessity of bending very far down to make adjustments.

Connected by hinges to the top of the same channel is a section 29 that may be opened downward to make the upper part of the ink motion and part of the plate cylinder accessible. The section 29 is held in position by pins 30 and 31 that are accommodated by suitably drilled holes in the side frame 2, as best shown in Fig. 4.

A spring 32, abutting against a bracket 33 secured to the guard section 29, pushes against a collar 34 on the pin 30, thereby causing the pin 30 to remain extended beyond the guard. The same construction is used on the pin 31. Manipulation of a handle 35, Fig. 2, pivotally mounted on the inside face of the section 29, will cause links 36 and 37 to withdraw the pins 30 and 31 respectively and allow the guard section 29 to be opened and lowered.

When the section 29 is in closed position it becomes a support for the section 38 that covers the plate cylinder 3. The section 38 is carried at the upper end by hinge studs 39 resting in brackets 40 secured to the side frame 2. Said hinge stud will allow the section 38 to be raised by pivoting upward, allowing the pressman to reach the plate cylinder 3.

The sections 19 and 29 allow easy access to the distributing roll surfaces, both for roller adjustment and removal. The door 41, which is hinged to the cover 1 at the end of the press, is swung outward to expose the roller ends and sockets in which rollers rotate. Said door is securely fastened in position by a locking handle 42 which engages with the bracket 27.

It is now evident that the guards, covers and doors cooperate in making this press completely enclosed. The openings at both ends of the unit are closed up, and the outside of the press is covered from the floor line to above the plate cylinders. The arrangement of the guards will

eliminate all ink fog from the press room and allow the pressman to carry on his work on the machine efficiently.

It will be noted that a ductor type fountain is used. A fountain roll 51 in a fountain bowl 52 is partially submerged in ink and is rotated therein accumulating a supply of ink on its surface. A ductor roll 53, which is oscillated back and forth between the fountain roll 51 and ink drum 8, is 10 rotatably mounted at the end of lever arms 54.

When the ductor roll 53 is placed against the fountain roll 51, an accumulation of ink will be picked up which will be deposited on the ink drum 8. The ink drums 7 and 8 are arranged 15 with a plurality of transfer and distributing rolls in such a manner that a thin film of ink is carried to form rolls 58 and 59 which are in contact with printing plates carried on the plate cylinder 3 and will transfer to the plates on said cylinder a 20 sufficient quantity of ink to produce a properly printed page.

The fountain roll 51 picks up a quantity of ink far in excess of that required, and it is common practice to employ a blade placed at an 25 angle to the fountain roll to remove the extra ink. The fountain blade 24 is secured to the fountain back 62 which is itself secured to the fountain bowl 52 becoming a partial cover thereof. The plurality of screws 28 threaded into the 30 fountain back 62 is brought against the blade 24 for the purpose of adjusting clearance between said blade and the fountain roll 51, thereby regulating the amount of ink supplied to the ductor roll 53.

Each screw 28 is made with a head 25a designed to accommodate a socket 66 of an extension rod, part of the screw 28, that is carried in a guard 19. Said guard is composed of sections which are removable, each section being in alignment with a newspaper page. A spring 67 abutting the guard 19 and a collar 68 attached to the extension rod 28 causes the socket 66 to be held securely in place over a screw head 25a. A thumb screw type head 25 on the screw 28 simplifies the screw adjustment. Therefore, it is evident that the removal of any section of the guard 19 from the press will cause the screw 28 to be removed. It is common practice to make newspaper presses four pages wide, in which case there would be 50 four guard sections 19 per fountain back.

This is a desirable feature when using an auxiliary fountain for color as shown in Fig. 9. Adjusting screws 28 may be used in shutting off the ink supply for the page desired and the guard section will be removed so that a color fountain 55 71 can be bolted in position on the fountain back 62, as shown.

A color fountain roll 70 is carried in the fountain 60 71 so that it is partially submerged and rotates in the colored ink. A fountain blade 72 is secured to a fountain back and cover 73. Adjusting screws 74 regulate the amount of ink transferred to a ductor roll 75 rotatably mounted in the end of lever arms 76. The ductor roll lever arm 76 is operated by a cam 77 secured to a fountain roll drive shaft 81 and acting against a cam roll 78 mounted in a lever arm 76. A spring 79 attached to said arm and secured to the fountain back 73 holds the ductor roll 75 against the fountain roll 70. The cam action will cause the roll 75 to be moved against an ink drum 80 which will pick up the color from the ductor roll and distribute the ink film to the plate cylinder 3 through the regular distribution system, already described.

A shaft 82 is connected to and rotates proportionally to the main drive through mechanism not shown. Said shaft is made on one end in the form of a clutch jaw 83 to engage a shaft 84. Mounted on the shaft 82 is a gear 85 that operates a gear 86 to which is secured a bevel gear 87, and both of which are carried by a shaft 88 mounted in suitable bearings 89. The bevel gear 87 drives a gear 91 mounted on one end of a shaft 92. To the other end of the shaft 92 is fastened a gear 93 meshing with a gear 94 secured to the shaft of the main fountain roll 51. It is evident, therefore, that the operation of the press will cause the fountain roll 51 to operate.

When using the auxiliary color fountain it is necessary to provide a suitable drive. The shaft 84 is carried by bearings 95 and 96 in a casing 97. Mounted on said shaft 84 is a helical gear 98 that drives a gear 99. Said gear 99 is attached to a shaft 60 also carried in the casing 97 by bearings 61 and 65. The shaft 60 extends beyond the casing 97 and by a coupling 63 is connected to the auxiliary fountain roll shaft 81. It should be noted that the casing 97 and its component parts may be removed as a unit from the gear case 64 when the color fountain is not used and the opening in the casing 64 may be concealed by a suitable cover.

It is evident that a simple and suitable drive is obtained for use with a color fountain.

The adjusting screw extension rod guard 19 in Fig. 8 becomes 19a, 19b, and 19d in Fig. 12. Said guards are each individually removable. The guard which would be 19c and placed between the guards 19b and 19d has been removed and replaced with an auxiliary ink fountain 71. Previous to removing the guard 19c the adjusting screws 28 have been set to cut off the ink supply in this section. It is also possible to prevent ink from the main fountain from feeding by removing or setting off the main ductor roll 53. This would be preferred where the main fountain of that particular ink motion was not to be used on any of the four pages.

When set in position, the auxiliary fountain 71 is driven by the shaft 81 through a driving collar 100, fastened thereon, cooperating with a driving plate 101 secured to the shaft 81 of the fountain roll 70. Any combination of one to four fountains may be added, the drive being secured by suitable change in the length of the shaft 81.

In multiple arrangement, a plate 102 will become a driver similar to the collar 55 and will cooperate with a plate similar to the plate 101 on the next fountain.

As shown, a margin screw 103 is not supplied with an extension rod as this is infrequently adjusted. A suitable recess 104 is provided at this position to make it available for adjustment by a wrench, if necessary, and to allow adjustment in the event it is desired to do so.

It is apparent therefore that an apparatus is devised for optionally installing one or more small page wide fountains by removing detachable parts of the main fountain back and that when this is accomplished, both the main and auxiliary fountains are located on the same side of the main center line of the ink motion.

Having thus described our invention and the advantages thereof, we do not wish to be limited to the details herein disclosed, otherwise than as set forth in the claims, but what we claim is:

1. A printing press comprising printing couples located at the top thereof, a press frame supporting the couples and of an arch formation, inking mechanisms comprising horizontal rolls and cylinders located in vertical alignment within the two sides of the frame, covering panels movably mounted on the frame for enclosing the sides of the couples and inking mechanism and for exposing them when desired, said inking mechanisms comprising vertical fountain blade adjusting screws having screw manipulating keys at their upper ends, for the purpose described, adapted to be exposed for adjustment, and removable guard sections or cover plates on which said screws are mounted and with which they are removable.

2. A printing press comprising printing couples located at the top thereof, a press frame supporting the couples, inking mechanisms comprising horizontal rolls and cylinders located in vertical alignment within the two sides of the frame, and an auxiliary color inking mechanism supported by, and constituting a cover for part of, the first named printing mechanism.

3. A printing press comprising printing couples located at the top thereof, a press frame supporting the couples, inking mechanisms comprising horizontal rolls and cylinders located in vertical alignment within the two sides of the frame, an auxiliary color inking mechanism supported by the first named printing mechanism and comprising an auxiliary ductor roll and an auxiliary ink drum arranged to transfer color to the inking mechanism.

4. A printing press comprising printing couples located at the top thereof, a press frame supporting the couples, inking mechanisms comprising horizontal rolls and cylinders located in vertical alignment within the two sides of the frame, an auxiliary color inking mechanism supported by the first named printing mechanism and comprising an auxiliary ductor roll and an auxiliary ink drum arranged to transfer color to the inking mechanism, and a cam and spring for operating the auxiliary ductor roll.

ELIZABETH OGDEN WOOD,
Executrix of the Estate of Henry A. Wise Wood,
Deceased.

CHARLES L. RICARDS.
